UNITED STATES PATENT OFFICE.

CARL LAWRENCE MATTISON, OF BELOIT, WISCONSIN, ASSIGNOR TO C. MATTISON
MACHINE WORKS, OF BELOIT, WISCONSIN, A CORPORATION OF WISCONSIN.

SURFACING-MACHINE.

1,191,981.

Specification of Letters Patent. Patented July 25, 1916.

Application filed December 21, 1914. Serial No. 878,228.

To all whom it may concern:

Be it known that I, CARL LAWRENCE MATTISON, a citizen of the United States, residing at Beloit, in the county of Rock and State of Wisconsin, have invented certain new and useful Improvements in Surfacing-Machines, of which the following is a specification.

This invention relates to a surfacing machine of the type generally known as a rubbing or polishing machine, since it is usually employed for rubbing the varnished surface of an article of furniture during the process of "finishing" such surface. The machine, however, is also adapted for sandpapering and other similar operations.

It is one of the objects of the present invention to produce an extremely compact machine of this character and one which is shorter in length than similar machines heretofore known.

Another object is to provide an improved driving means for reciprocating the rubbing heads.

25 The invention also refers to improved guide means for the rubbing heads.

Another object of the invention is to provide improved means for preventing the polishing material from splashing up onto the 30 bearings of the driving mechanism or onto the guideways for the rubbing heads.

Further objects and advantages will appear from the following detailed description.

35 In the accompanying drawings, Figure 1 is a longitudinal vertical sectional view through a surfacing machine embodying the features of my invention. Fig. 2 is a horizontal sectional plan view taken in the 40 plane of line 2—2 of Fig. 1. Fig. 3 is a transverse vertical sectional view on line 3—3 of Fig. 1. Fig. 4 is a fragmental transverse section illustrating the guide means for the rubbing heads.

45 The machine shown in the drawings, which represents the preferred embodiment of my invention, comprises an elongated lower portion of generally rectangular form and a circular upper portion disposed with 50 its axis vertical and mounted on the middle of the lower portion. A pair of handles 9 fixed on opposite ends of the lower portion provide means for carrying the machine from place to place. The lower portion 55 comprises a rectangular base frame 10 open

at its lower side, and a top member 11 closing the upper side of said frame and having a circular central portion 12. The upper part 13 constitutes the casing of an electric motor, the lower side of the casing being 60 open. Between the lower edge of the casing 13 and the upper edge of the central portion 12 is a spider 14 having a central opening forming a bearing for the armature shaft 15 of the motor. Below the spider 14 the 65 said armature shaft has teeth cut therein to form a driving pinion 16. This pinion meshes with a pair of oppositely disposed gears 17 which are fixed on the hubs of spur pinions 18, the latter pinions being rotatable 70 upon pins or shafts 19 which are seated in sockets 20 in a transverse web of the member 11 and have squared upper ends 21 fitting into corresponding openings in the spider 14. The spur pinions 18 mesh with 75 a central gear 22 which has a depending sleeve or hollow shaft 23 mounted in a ball bearing 24 in the member 11. Within the gear 22 is a bushing 25 which forms a bearing for the reduced lower end of the armature shaft 15. The described gearing reduces the high speed of the motor to a lower speed of the drive shaft or sleeve 23.

A double-throw crank-member 26, which may be of any suitable construction, has its 80 upper end threaded into the lower end of the sleeve 23 and has its lower end rotatably mounted in a ball-bearing 27 mounted on a cross-bar 28 which is suitably supported at its ends by the rectangular base frame 10. 90

Pitmen 29 are connected to the opposite cranks of the crank-member 26, said pitmen extending in opposite directions from said member and being attached at their other ends to pivot pins which are seated in 95 standing bosses 31 on the rubbing heads 32. Preferably, ball bearings 33 are provided at both ends of the pitmen 29.

Each of the rubbing heads 32 is provided on its upper side with a pair of upwardly pointing wedge-shaped ribs 34 adapted to slide in guide grooves 35 formed in the lower faces of inwardly extending ledges 36 on the sides of the base frame 10. Vertical plates 43 are secured to the outer sides of the base frame and form depending flanges which overlap the sides of the rubbing heads as shown in Fig. 3. Below the ribs 34 the heads 32 are horizontally undercut or grooved to receive supporting ribs 37 which 110

are formed on the inner sides of the plates 43.

The two rubbing heads have horizontal guard extensions or flanges 38 extending inwardly toward each other, and coöperating with a central transverse plate 39 which is stationarily secured at its ends to opposite sides of the base frame 10. In the present instance the plate 39 is flat and one of the flanges 38 lies above and the other below said plate. At their outer sides the rubbing heads are slotted as at 40, and are provided with flanges 41 to coöperate with stationary end plates 42 which extend from side to side of the base frame and completely close the open lower side thereof at the ends. The plates 42 are turned up to provide end flanges 42^a which in effect constitute a continuation of the end walls of the base frame.

The rubbing heads 32 fit snugly between the plates or flanges 43 at opposite sides of the base frame so that the lower side of said frame is completely closed at all times by the central plate 39, the rubbing heads 32, and the end plates 42. This prevents any of the polishing material, commonly used in finishing furniture, from splashing up against the bearings of the drive mechanism, or against the guideways for the rubbing heads.

The lower side of each rubbing head has beveled faces 44 extending transversely of the direction of reciprocation of the rubbing heads. A rubbing shoe 45 for each head is provided with undercut grooves 46 in a stationary wall thereof and in a movable clamp-bar 47 to coöperate with the beveled faces 44 on the rubbing head. The clamp-bar 47 is adjustably secured to the rubbing shoe by means of set screws 48. To the lower faces of the rubbing shoes are secured layers of felt 49 or other suitable material. If the machine is to be used for sand-papering, a sheet of sand-paper is attached to the lower side of each rubbing shoe.

It will be noted that when the rubbing heads are in their innermost position, as shown in Fig. 1, the driving pitmen 29 overlap each other to a considerable extent, so that a very compact construction is afforded, and the rubbing heads can approach each other very closely. By providing the central stationary splash-plate 39, the overlapping inner flanges 38 can be made much shorter so that the rubbing heads may come close together, and the said stationary plate will close the gap between the flanges when the rubbing heads are in their outermost position, so as to keep the lower side of the casing constantly closed.

While I have herein described the preferred embodiment of my invention in considerable detail, I do not thereby intend to limit the invention to the form disclosed, except as recited in the appended claims.

I claim as my invention:

1. A surfacing machine having, in combination, a rectangular base frame, a top member closing the upper side of said frame and having a central circular chambered portion projecting upwardly, an electric motor disposed with its axis in a vertical plane and having its casing shaped to fit upon and be supported by the upper edge of said circular portion, the motor having an armature shaft projecting down into the circular portion, a horizontal web extending across said circular portion and having bearings therein, reducing gearing supported in certain of said bearings and connected to said armature shaft, a drive member mounted in a bearing in said web in alinement with the armature shaft and connected to said gearing to be driven at a reduced speed by the latter, a pair of slidable rubbing heads mounted in said base frame, and means operatively connecting said heads to said driving member.

2. In a surfacing machine, in combination, a body having an open lower side, a centrally positioned stationary member partially closing the said open side, and a pair of surfacing elements reciprocably mounted on the body at opposite sides of said member and arranged to move toward and away from said member, said elements having parts coöperating with said stationary member to assist in closing said open side.

3. In a surfacing machine, in combination, a body having an open lower side, a pair of surfacing elements reciprocably mounted at the lower side of the body, a stationary horizontal plate mounted on the body between said elements, and horizontal guard flanges on the surfacing elements projecting toward each other and lying one above and one below said horizontal plate to coöperate therewith in closing the said open side of the body.

4. In a surfacing machine, in combination, a body having an open lower side, members fixed at opposite ends of the body to close said lower side at the ends thereof, and surfacing elements reciprocably mounted on the body and being slotted to receive the said members in the sliding movements of said elements.

5. In a surfacing machine, in combination, a body having an open side, a pair of surfacing elements reciprocably mounted on the body, stationary plates extending inwardly from opposite ends of the body for closing said open side at the ends thereof, and flanges adapted to slidably coact with said plates to assist in closing the said open side.

6. In a surfacing machine, in combination, a body having an open lower side, a pair of surfacing elements reciprocably mounted at the lower side of the body, a stationary central member and stationary

end members arranged to partially close said lower side, and a pair of surfacing elements adapted to coact with said central member and end members, whereby to maintain said 5 lower open side completely closed at all times.

7. In a surfacing machine, in combination, a body having an open lower side, a central horizontal plate and end horizontal 10 plates partially closing said open side, and a pair of surfacing elements reciprocably mounted adjacent to the open side and having horizontal flanges to slidably coact with said horizontal plates, the inner flanges lying 15 one above and one below the central plate.

8. In a surfacing machine, in combination, a body having an open lower side, a centrally positioned stationary member adjacent to the lower side, a pair of surfacing 20 elements reciprocably associated with the body at opposite sides of said member, flanges on said elements extending toward each other and overlapping each other when 25 the surfacing elements are at their inner end of the stroke, the said member filling the gap between said flanges when the surfacing elements are at the outer ends of their stroke.

30 9. A surfacing machine comprising an elongated rectangular base frame, a top member closing the upper side thereof and having a central circular portion, an electric motor disposed with its axis in a vertical plane and mounted on said circular portion, a pair of slidable surfacing elements, and means within said base frame connecting the motor to said surfacing elements for reciprocating the latter.

40 10. In a surfacing machine, in combination, a rectangular base frame, a top member closing the upper side of said frame and having a circular central upwardly projecting portion, an electric motor disposed with 45 its axis vertical and comprising a casing having an open lower end resting upon the said circular central portion of the top member, reducing gearing mounted in said top member and driven by the motor, a pair of 50 slidable rubbing heads mounted in said base frame, and crank means connecting the reducing gearing to said rubbing heads for reciprocating the latter.

11. In a surfacing machine, in combination, a base having members provided at 55 their lower faces with downwardly opening V-shaped guide-grooves, a pair of rubbing heads mounted beneath the base, a pair of upwardly pointing wedge-shaped ribs

mounted on opposite sides of each of the 60 rubbing heads, the latter being undercut or grooved at opposite sides, and rails engaging in said grooves for supporting the rubbing heads when the machine is lifted.

12. In a surfacing machine, in combination, a base having therein downwardly facing V-shaped guide-grooves, a pair of rubbing heads mounted beneath the base frame, and upwardly pointing wedge-shaped ribs on said rubbing heads adapted to slide 70 in said V-shaped grooves in the base.

13. In a surfacing machine, in combination, a rectangular base frame having inwardly extending ledges at opposite sides thereof, said ledges having in the lower faces 75 downwardly opening V-shaped guide-grooves, a pair of rubbing heads mounted beneath opposite ends of said base frame and each having a pair of upwardly pointing wedge-shaped ribs adapted to enter and slide 80 in said guide-grooves, and means fixed on the base frame and engaging in said heads for supporting the latter when the machine is lifted.

14. In a surfacing machine, in combination, a rectangular base frame having inwardly extending ledges running along opposite sides thereof, the said ledges having in their lower faces downwardly opening 85 V-shaped guide-grooves, a pair of rubbing heads mounted beneath opposite ends of said frame, a pair of upwardly pointing wedge-shaped ribs on opposite sides of each rubbing head adapted to enter said guide-grooves, each of said heads being undercut 90 or grooved at opposite sides, and a pair of rails fixed at the under side of said ledges and entering the grooves in the rubbing heads for supporting the latter when the machine is lifted.

15. In a surfacing machine, in combination, a body having an open lower side, a pair of surfacing elements mounted at said lower side to reciprocate toward and away from each other, and means for maintaining said lower side closed against the entrance 100 of material from below, said means comprising a member stationarily mounted on the body between said surfacing elements and parts moving with said surfacing elements and arranged to overlap said member. 105 110

In testimony whereof, I hereunto set my hand in the presence of two witnesses.

CARL LAWRENCE MATTISON.
